UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed December 27, 1919. Serial No. 347,740.

To all whom it may concern:

Be it known that I, THOMAS LUND, a citizen of the United States, residing at Beverly, in the county of Essex and State of Massachusetts, have invented certain Improvements in Heel-Building Machines, of which the following description, in connection with the accompanying drawings, is a specification, like reference characters on 10 the drawings indicating like parts in the several figures.

This invention relates to heel building machines and more particularly to that type of such machines whereby a series of heel lifts 15 died out of leather, or other character of sheet material, are assembled and formed into a heel.

In the commercial manufacture of boot and shoe heels it is now a common practice 20 to manually assemble a number of heel lifts in a heel form and secure them together by driving one or more fastenings into the pile. The limited production incident to this 25 practice has led to the development of full automatic heel building machines, which, while answering the requirements of the larger and more extensive factories, have not been economically applicable to the building of heels in the average manufac- 30 turing plant. As an outgrowth of this condition a heel building machine has been developed to respond to the demands of the average factory by making the machine semi-automatic, a term that serves well to 35 identify that type of heel building machine where the heel lifts are taken from a source of supply, pasted and assembled into a heel pile automatically and then secured together by a manually controlled fastening inserting 40 machine or nail driver associated with the assembling mechanism.

Machines of this type are more simply constructed and operated than the full automatic machines and their productive capacity as compared with the manual assembly 45 of the heel lifts under the old practice is greatly increased, and one of the objects of the present invention is to provide a machine of the so-called semi-automatic type 50 which will be simple in construction and effective in its operative capacity for increased production.

In automatically assembling the heel lifts for treatment in the heel form in machines

of this general type, the lifts are piled up 55 one-on-top of another until the desired number of lifts have been accumulated to complete the heel pile, and various means have heretofore been suggested for this purpose. In some suggested instances, the heel lifts 60 have been moved from a source of supply onto other partially formed heel piles and an intermittent or step movement has been given the partially formed piles after each 65 delivery of a lift thereto, until the completion of the leading pile of the series which has then been delivered to the nailing mechanism. In other cases the lifts have been placed upon a support from which they have 70 been delivered to partially formed heel piles by an intermittently moving assembling 75 mechanism. In still other suggested constructions the heel lifts have been delivered to a carrier having a uni-directional movement for serially delivering the lifts to the 80 forms.

With respect to this feature, the present invention differs from all the prior suggestions and is characterized by lift supports arranged in stepped relation, and automatic 80 means for successively advancing the lifts from their stepped supports and progressively forming them into a pile. This constitutes one of the important features of the invention and is preferably carried into 85 practice by arranging the stepped supports with their supporting surfaces in different horizontal planes and sliding the lift or lifts from a higher stepped support onto a lift on the next lower stepped support by an assem- 90 bling mechanism which is automatically moved the full distance of the line of supports, the effect being to gather the series of lifts on the stepped supports into a pile by a single movement of the assembling 95 mechanism.

It is now the common practice to supply a quick-drying adhesive or glue to the contacting surfaces of the lifts when they are moved from the source of supply to be 100 piled. The adhesive is applied while in a liquid or semi-liquid condition and usually gums up the various parts of the machine, a fact which becomes particularly observable when the pile of lifts are subjected to 105 pressure in the heel form. The present invention aims, among other things, to overcome this objectionable condition incident to

the application of a liquid adhesive to the lifts while they are being built into a heel, and another important feature of the invention consists in supplying heel lifts which 5 have been previously gummed and dried, and moistening or tempering the gummed surface as the lifts are moved from the source of supply to assembling position. Since the lifts are delivered to stepped 10 lift supports the moistening means, which is conveniently formed as a pad, may have stepped portions to contact with the gummed surface of the lifts as they move towards the stepped supports.

15 When the heel lifts have been formed into a heel pile they are to be secured together by one or more fastenings or nails driven into the lifts while the pile of lifts are under pressure in the heel form. In the present 20 invention the heel lifts are automatically assembled into a pile from the stepped lift supports, and a further important feature of the invention in this respect consists in moving the completely formed heel pile into 25 the heel form for the action of the pressure members and nailing instruments.

In effecting this movement of the completely formed heel pile into the heel form, it is desirable to obviate, as far as possible, 30 any disturbance of the piled lifts relative to each other. Another important feature of the invention, therefore, consists in a heel form having a heel jaw or clamp which is opened to admit the heel pile as it is advanced by the assembling mechanism and is then closed to hold the heel pile for the pressing and nailing operation. During the transfer of the heel pile to the heel form by the assembling mechanism, operation of the 35 pressing and nailing mechanism should be prevented, otherwise injury to the mechanism is liable to result. A still further feature of the invention, therefore, consists of means connected to the assembling mechanism which is rendered effective to prevent 40 operation of the pressing or nailing mechanism during the operation of the assembling mechanism.

Other novel features and new combinations of parts in addition to the above will 45 herein after be described in connection with the accompanying drawing, which, while showing one good practical form of the invention, are not, however, to be understood as limiting the invention to the details disclosed, except as pointed out by the claims.

In the drawings:

Fig. 1 is a front elevation of a machine embodying the present invention, some of 50 the parts being broken away;

Fig. 2 is a plan view, some of the parts being shown in section and others broken away for clearness of illustration;

Fig. 3 is a section on the line 3—3 of 55 Fig. 2;

Fig. 4 is a section substantially on the line 4—4 of Fig. 1, some of the parts being shown in elevation to make clear their association with other elements;

Fig. 5 is a section substantially similar to 70 that of Fig. 4 showing the parts in another position;

Fig. 6 is a section on the broken line 6—6 of Fig. 4 showing more particularly the means for controlling the automatic action 75 of the assembling mechanism and for opening and closing the heel mold;

Fig. 7 is a detached detail in perspective showing the series of pushers for simultaneously moving a series of heel lifts from 80 sources of supply and delivering them to the stepped lift supports.

The machine frame may be of any usual or appropriate character for supporting the operating parts and as herein illustrated comprises the table or support 1 with which 85 is associated the heel lift assembling mechanism and the frame 2 connected to the table 1 and adapted to support the operating parts of the pressure and nailing mechanisms. 90 The combined frame work may be appropriately supported from suitable base members. Mounted in bearings 3 on the machine frame is the driving shaft 4 which may be continuously driven from a suitable source 95 of power through the driving member 5 which may be constituted as a driving pulley to receive motion from a line shaft through belting connection, as usual. Loosely mounted on the drive shaft 4 is the sleeve 6 carrying the worm 7 which meshes with a worm wheel 8 mounted on the actuating shaft 9 for the heel lift assembling mechanism. The sleeve 6 carrying the worm 7 is adapted to be operatively connected at times to the 100 drive shaft 4 through a clutch connection which is herein shown as a clutch of the Horton type. This clutch, as indicated in Figs. 4 and 5, is provided with the opposite stop lugs 10 and 11 which are adapted to 105 cooperate with the swinging dogs 12 and 13, the construction being such that when either of the dogs 12 or 13 is in its stopping position for engagement by one of the lugs of the Horton clutch, the worm sleeve 6 will 110 be freed from its operative connection with the drive shaft, and when both dogs 12 and 13 are withdrawn from engagement with the lugs 10 and 11, as indicated in Fig. 4, the worm sleeve 6 will be operatively engaged with the drive shaft and be rotated thereby to effect rotation of the actuating 115 shaft 9.

The actuating shaft 9 may be carried in suitable bearings in the machine frame and extends transversely of the frame, as indicated in Fig. 2. The shaft 9 carries the sprocket wheel 14. Mounted in a suitable bearing 16 opposite the sprocket wheel 14 is an idler sprocket 15. A sprocket chain 17 120

extends about the sprockets 14 and 15 and is actuated from the shaft 9, the construction being such that when the shaft 9 is rotated through the means hereinbefore described, 5 the chain 17 will be given its automatic movement.

A series of magazines 18 is suitably mounted upon the table 1 and constitutes means for supporting a series of stacks of heel lifts 10 a. The magazines 18 may be arranged in alinement, as shown by Fig. 2, and connected to the supporting frame in any suitable manner, the details in this respect being non-essential. In the present instance of the invention four magazines are indicated, but, of course, the number of magazines may be varied in accordance with the number of lifts that are to be assembled into a heel pile.

The machine frame is provided with 20 guide-ways 19 for a series of feed slides or pushers 20, the function of which is to remove from the magazines a plurality of heel lifts sufficient in number to constitute a complete heel pile and deliver the heel lifts onto 25 stepped supports, presently to be described. The pushers 20 are adjustably attached by pin and slot connections 21 with fingers 22 extending from the push bar 23. The push bar 23 has connected thereto the guide member 24 which is adapted to slide towards and from the front of the machine in suitable 30 guide-ways 25. The pushers 20, Fig. 7, which are connected to the push bar 23 by the means hereinbefore described, are arranged in stepped relation, that is, the pusher at the left of the series, Fig. 7, is in a higher plane than the next pusher 20 of the series, and so on throughout the entire number of pushers. This relative position of 35 the pushers 20 is best effected by the arrangement of the guide-ways 19 in the machine frame. Likewise, the bottom or delivery ends of the magazines are formed in stepped relation in accordance with the 40 stepped relation of the pushers 20, the construction being such that when the pushers are actuated, as will more fully appear, each pusher will take the lowest heel lift from a magazine and simultaneously push or advance the series of heel lifts onto the heel lift 45 supports which will now be described.

Mounted on the machine frame is a series of stepped heel lift supports 26 arranged in alinement preferably parallel to the series of 50 magazines, with one of the lift supports opposite each magazine for delivery thereto of a heel lift from the associated magazine. It will now be obvious why the lower or delivery ends of the magazines are arranged in 55 stepped relation and why, also, the pushers 20 are similarly arranged.

The top or supporting surfaces of the stepped lift supports are arranged in different non-intersecting planes, which, as indicated 60 in the illustrated form of the invention,

are preferably horizontal. The term "stepped" relation is herein used to indicate a series of supports which progressively increase in height from one end of the series to the other and whose supporting surfaces 70 are in parallel non-intersecting planes. The difference in height of adjacent stepped supports should be equal at least to the thickness of a heel lift, the construction being such that when lifts are placed upon the stepped 75 supports, the highest lift of the series may be moved or advanced onto the next lift of the series and then the two advanced to the third lift of the series and so on throughout in order that when the lifts from all of the 80 steps have been assembled, a complete heel pile results.

In order to gather and form the lifts into a heel pile after a series of such lifts have been delivered to the stepped lift supports, the present invention provides an automatic assembling mechanism. In the present instance the sprocket chain 17, already described, has connected thereto a finger or pusher which is adapted to successively engage and move or advance the heel lifts from one stepped support to another until the entire series has been assembled into a heel pile. Mounted in suitable guides 27, 28, Figs. 1 and 3, and extending substantially parallel 90 to the line of heel lift supports, is a slide 29, Fig. 3, having a vertical slot or guide-way 30 in which is mounted the block 31. The block 31 is connected to the sprocket chain 17, as by the pin 32, Fig. 3, and as the 95 sprocket chain is moved by the sprocket wheels, as hereinbefore described, the slide 29 will be moved longitudinally to the left, Fig. 1, and back to its original position, the block 31 being free to move in the slot 30 of the slide 29. Rising from the slide 29 is the finger 33 which may be connected to the slide by means of the screws or other suitable devices 34, Fig. 3. The upper end of the finger 33 is extended into alinement with the 100 alined heel supports, as indicated at 35, Fig. 2, and has adjustably secured thereto the pusher head 36 which, as the sprocket chain and, perforce, the finger 33 is moved to the 105 left, Fig. 1, successively engages the lifts on the stepped lift supports and slides the lifts from the respective supports onto the lifts in the adjacent lower support until the entire series has been assembled into a heel pile. The head 36 may be connected to the finger 110 115 by the adjusting bolt 37 which may pass through a slot in the portion 35 of the finger and permit the head 36 to be properly adjusted relative to the other parts. In order that the head 36 may act as hereinbefore described, the stepped heel lift supports 26 are longitudinally slotted at 38 and 39 at each side of a central guide rib 40, and the head 36 is formed with the leg portions 41 which straddle the central rib 40 and serve to guide 120 125 130

the top or supporting surfaces of the stepped lift supports are arranged in different non-intersecting planes, which, as indicated 60 in the illustrated form of the invention,

the head 36 as it advances in the line of heel lifts.

The heel lifts that are placed in the magazines for assembling into heel piles may be of usual character, but in the present instance of the invention the heel lifts are preferably provided with an adhesive on one surface which is dried before the lifts are placed in the magazines, and as the lifts are pushed from the magazines for delivery to the stepped supports, the gummed and dried surface is moistened or tempered. The moistening or tempering action is best carried into effect by means of a pad 43 which may be of suitable absorptive material, such as felt or the like, and be held between the side clamping plates 44, best indicated in Figs. 1 and 2. The clamping plates 44 and the enclosed pad 43 may be secured in position between the magazines and the stepped heel supports by the screws or other fastenings 45 which preferably pass into a front portion 46 associated with the several magazines.

25 The pad between the plates 44 is supplied with the tempering liquid which is preferably water, by means of a pipe 47 connected to a source of supply and having branch connections 48 at intervals with the pad. A valve 49 in the pipe 47 serves to regulate the supply of liquid or water to the pad.

Since the heel lift supports are arranged in stepped relation, as described, and the heel lifts themselves are moved from the magazines in stepped relation onto the stepped supports, the lower active edge of the pad 43 is formed with stepped portions 50 which serve to contact with the upper surfaces of the heel lifts as they are moved from the magazines to the stepped supports.

When the heel pile has been assembled, it is to be placed in the heel form and then subjected to the pressing and nailing operation. The automatic assembling of the heel lifts from the stepped supports may, of course, be associated with different forms of pressing and nailing machines. In the present instance the pressing and nailing mechanism may be substantially the same as that disclosed in United States Letters Patent No. 1,056,720 granted March 18, 1913, to Eliphalet A. Tripp, wherein a beam or head constituting one of the presser members is moved to and from operative position with relation to the heel form, and the nailing of the heel pile is effected by actuation of the nailing mechanism when the beam or head is brought to its presing position.

As shown more clearly in Figs. 4 and 5, the head or beam 51 is of the general type of that shown and described in the above-mentioned patent and the action of the nailing mechanism is effected automatically by the forward movement of the beam or head into the pressing position, as more fully

described in the said patent. The head or beam 51 carries the presser member 52 yieldingly mounted in the head through the instrumentality of the spring 53, and a handle 54 serves as a convenient means for the attendant to move the beam or head into its operative or inoperative position relative to the heel form.

The heel form comprises the bottom plate 55 which is provided with nail driving passages 56 and the fixed side jaw 57 and the movable side jaw 58. The supporting surface of the bottom of the heel form is preferably arranged in the same plane as the lowest heel lift support 26, the construction being such that after the pile of heel lifts has been completed as hereinbefore described, they may be moved as a unit into the heel form, the movable jaw 58 at such times being open for the reception of the heel pile, as will more fully appear.

Below the bottom of the heel form is the nail block 59, Fig. 4, with which is associated the driver block 60 having the drivers 61 for driving nails which are delivered to the nail receiving openings in the nail block. Between the nail block and the driver block 60 are the rods 62 which serve to cause movement of the nail block and the driver block to and from driving and nail receiving position in unison. The driver head 63 has the usual reciprocating movement through toggle levers 64 only one of which is shown in the present illustration, but which may be as more fully described in said patent.

Mounted for sliding movement towards and from the front of the machine in suitable bearings 65, are the two slides 66, one each side of the beam or head 51. The slides 66 are provided with the guide-ways 67, Fig. 4, which may be formed by lugs 68 secured to the slides and suitably spaced apart. The guide-ways 67 are engaged by lugs or rolls 69 carried by the downwardly extending portion of the head 51, the construction being such that as the head or beam 51 is moved forwardly to operative position relative to the heel form, the slide bars 66 will be correspondingly moved, and, reversely, when the head or beam 51 is moved backwardly, the slide bar 66 will partake of such movement also. Mounted on the slide 66 are the brackets 70, Figs. 4 and 5, which are provided with the hook portions 71 adapted to engage complementary hook portions 72 on the driver block 60 when the latter is lowered from the position of Fig. 5 to that of Fig. 4 so that the driver block 60 may partake of the movement of the slide 66, the construction being such that when after a nailing operation the driver block 60 is lowered by the descent of the driver head, the hooks 71 and 72 interengage and on backward movement of the head or beam 51 the slide bar 66 carries the driver block and

nail block rearwardly into nail receiving position, substantially as indicated in Fig. 4. Nail chutes 73 extend upwardly from the machine bed to receive a charge of nails 5 from the nail distributor 74 which is provided with recesses 75 for two nails supplied from the race-way 76 which is kept charged with nails from a suitable hopper or nail pot 77, Fig. 4. The distributor 74, Fig. 4, may 10 be actuated by any suitable source of power to periodically deliver the nails head downward to the nail chutes 73, but in the present instance of the invention there is diagrammatically represented in Fig. 4 a rack member 15 indicated by dotted lines and pivoted at 78 and connected at 79 to an operating member 80 driven by a suitable eccentric 81 which receives motion from the shaft 9 through a series of speed rotation gears 82, 20 the construction being such that the nail distributor will supply two nails to the nail block when the latter is in its rearward position, as indicated in Fig. 4, and when the nail block is moved forwardly into its 25 operative relation with the beam of the heel form, the nails will be driven into the heel, the head or beam 51 at such times being in its forward or operative position relative to the form and subjecting the heel pile to 30 pressure.

Reference has hereinbefore been made to the feed of the heel lifts simultaneously from the magazines onto the stepped supports, and such feeding movement is effected 35 in the present instance of the invention by the backward movement of the head or beam 51 through a train of mechanism best indicated in Figs. 4 and 5. The guide member or bar 24 which actuates the pusher bar 23, 40 Fig. 7, is connected by link 83 to the upper end of a lever 84 mounted on a shaft 85 supported in the machine frame. The shaft 85 is rocked through the medium of an arm 85*, the bifurcated lower end of which engages a 45 pin 87 mounted on the slide bar 66, the construction being such that as the beam moves backwardly, the pusher bar 23 is moved forwardly to transfer from the series of magazines a plurality of heel lifts simultaneously and deliver the lifts to the stepped lift supports.

When the beam or head 51 is moved to its rearward or inoperative position, the movable or swinging jaw 58 of the heel form should be opened to receive the pile of heel lifts and the assembling mechanism should be set in operation. On the other hand, when the beam or head 51 is moved to its operative position over the heel form, the 55 movable or swinging jaw 58 should be closed and the automatic assembling mechanism be made inoperative.

The swinging jaw 58 is connected to the upper end portion of the rod 88, Figs. 4 and 65 5, and the rod 88 carries the toothed gear 89

which meshes with another toothed gear or rack 90 mounted at 91, Fig. 2, and having a bifurcated end portion 93 which engages a roll 94 on one of the slide members 66, Fig. 6, the construction being such that 70 when the beam or head 51 is moved backwardly or towards its inoperative position, the roll 94 will, through the train of mechanism described, swing the jaw 58 into its open position, as indicated by full lines, 75 Fig. 2, and when the beam or head 51 is moved to its forward or operative position, the roll 94 will close the swinging jaw 58 into its dotted line position, Fig. 2.

The stop dogs 12 and 13 for the Horton 80 clutch, as indicated in Figs. 5 and 6, are normally under the influence of their respective springs 95 and 96, the former of which tends to throw the stop dog 12 into position to engage one of the stop lugs 10 or 85 11 of the Horton clutch and the other of which, 96, normally acts to move the stop dog 13 out of operative relation with the Horton clutch, the construction being such that only when both stop dogs are 90 disengaged or moved outwardly relative to the Horton clutch, will the latter transmit movement to the automatic assembling mechanism. The stop dog 13 for the Horton clutch, as more clearly indicated in Fig. 6, has a 95 collar 97 which normally limits the disengaging movement of the dog under the action of the spring 96. Connected to the dog 13 at 98 is the rod 99 which extends into a sleeve 100 pivotally connected at 101 to a 100 bell crank lever 102 pivoted at 103 and having a toe 104 which is adapted to be engaged by a lug 105 on a slide bar 106 which is connected to the automatic assembling mechanism and by virtue thereof causes the lug 105 105 to actuate the bell crank 102 when the assembling mechanism has made an assembling and feeding movement and returned to its initial position, as indicated in Figs. 1 and 2.

Pivotaly mounted on the sleeve 100 at 107 is a latch 108 the end 109 of which is adapted to be engaged with a slot or notch 110 in the rod 99, Fig. 6. A spring 111 normally acts upon the latch to hold its end 109 engaged with the notch 110 of the rod, the construction being such that when the bar 106 is moved into position indicated in Fig. 6, as the assembling mechanism approaches its initial positions after having assembled and moved a heel pile to the heel form, the sleeve 100, and, perforce, the bar 99, will move the dog 13 into position to engage one of the stops 10 or 11 of the Horton clutch, 115 as indicated in Fig. 6. The slide 66, Fig. 6, has a bunter 112 adjustably connected thereto which, as the slide 66 moves to its rearward position under the actuation of the beam or head 51, will engage a lug 113 on the dog 12 and serve to move the dog 12 out 120 125 130

of engagement with the lugs of the Horton clutch and, as the slide 66 moves frontwardly, which is coincident with the movement of the beam or head to its operative position, the bunter 112 will move frontwardly and permit the dog 12 to move into engagement with the Horton clutch stop lugs and, perforce, hold the automatic assembling mechanism at rest.

10   Mounted upon one of the slides 66 is a cam trip member 114 which is adapted to engage the latch 108 and trip it from engagement with the rod 99 as the slide 66 moves frontwardly to place the head or beam in operative position relative to the heel form, the construction being such that as the latch 108 is tripped by frontward movement of the slide 66, the dog 12 will be moved to its inoperative or disengaging position relative to the Horton clutch and the dog 12 will be moved into its operative or holding position, so that the automatic heel assembling mechanism will remain at rest. When the beam or head 51 is moved backwardly to its inoperative position after a pressing and nailing operation, the bunter 112 will strike the lug 113 on the dog 12 and remove it from engagement with the lugs of the Horton clutch, thereby starting into operation the 15 automatic heel assembling mechanism. As the assembling mechanism moves in its heel lift assembling path, the bar 106, presently to be more fully described, will be moved to the left out of engagement with the bell 20 crank 102, with the result that the spring 115 which normally acts upon the sleeve 100 to move it frontwardly, will carry the end 109 of the latch 108 into engagement with the notch 110 of the rod 99, so that on backward movement of the bar 106 after the delivery of a heel pile to the heel form, the 25 projection 105 will move the bell crank 102 and, perforce, trip the clutch and stop the operation of the automatic assembling mechanism. Thus it will be understood that when a pile of heel lifts is being subjected to the pressing and nailing operation, the 30 automatic heel assembling mechanism is at rest, and when the pressing and nailing operation is completed and the beam or head 51 is moved to its rearward position, the assembling mechanism is rendered operative.

35   The bar 106, hereinbefore referred to, is best shown in Figs. 1, 2 and 3. It is connected to the slide 29, Fig. 2, by suitable means, such as the screw 116, Fig. 3, and is guided in its longitudinal movement in a suitable guide-way 117.

40   When the automatic heel lift assembling mechanism is operating to successively move the heel lifts from their stepped supports and form them into a heel pile and then delivering the formed heel pile to the heel form, it is desirable that the pressing and nailing mechanism be prevented from actu-

ation by the attendant or moved to their operative positions. To this end the bar 106 is moved transversely of the machine by the heel lift assembling mechanism and extends frontwardly of the front end portions of the slide 66 which, being connected to the beam or head 51, prevents movement of the head or beam to its operative position relative to the heel form while the automatic assembling mechanism is in operation.

45   When the pile of heel lifts has been subjected to pressure and nailed, it is desirable that the pile of lifts be now ejected from the machine to permit another pile of lifts to be placed in the heel form by the assembling mechanism. To this end the present invention provides an ejecting mechanism actuated by movement of the beam or head. The beam or head 51 has connected thereto the links 118, Fig. 2, to which is jointed the 50 cross head 119. A rod 120 extends loosely through the cross head 119 and has a stop 121. The frontward end of the rod 120 is secured to a lug 122 formed as part of a cross member 123 and a spring 124 is interposed 55 between the cross head 119 and lug 122.

60   From the cross piece 123 there extends forwardly two side members 125 which travel in the guide-ways 126 in the machine frame at opposite sides of the heel form, as indicated in Fig. 2. Projecting forwardly from the cross piece 123 is the heel ejector 127, and oppositely disposed thereto is the 65 pad 128 on the front cross piece 129 which is carried by the side members 125.

65   Mounted in bearings formed in the machine frame below the cross piece 123 are the catches 130, Figs. 4 and 5, which are normally held upwardly projected by the 70 springs 131 and in front of the cross piece 123 when the head or beam 51 is in its rearward position.

75   When the head or beam 51 is moved frontwardly into operative position, the spring 124 is placed under tension and the cross piece 123 is held by the catches 130 from moving frontwardly, as indicated by full lines in Fig. 5. When the beam or head 51 is given its downward movement to compress the heel pile, lugs 132 on the side of the beam members are moved downwardly into engagement with lugs 133 carried by the catches 130 and depress the catches, thereby freeing the ejector to the expansive action of the spring 124, so that when the head is moved upwardly and pressure is removed from the now compressed and nailed heel lifts, the spring 124 asserts itself and throws the heel forwardly where it drops through the opening 134 formed on a 80 frontwardly projecting portion of the machine frame, as indicated in Figs. 2 and 5. After the compressed and nailed heel pile has been ejected, and as the head or beam 51 is moved to its rearward posi-

tion, the swinging jaw 58 of the heel form opens to permit the bodily movement of another heel pile into the form.

I claim:

5. 1. In a heel building machine, the combination of means for holding a series of stacks of heel lifts, heel lift supports arranged in stepped relation with their supporting surfaces in different planes, means for simultaneously moving a series of lifts from the stacks to said supports, and assembling means for successively moving the lifts one over another from the supports and forming them into a heel pile. 70
15. 2. In a heel building machine, the combination of means for holding a series of stacks of heel lifts, horizontal heel lift supports arranged at different levels opposite the respective stacks, means for simultaneously delivering a series of heel lifts to the supports, and means for successively moving the heel lifts one over another from their supports and progressively assembling them into a heel pile. 80
25. 3. In a heel building mechanism, the combination of means for holding a series of stacks of heel lifts, heel lift supports arranged in stepped relation with their supporting surfaces in different planes, means for simultaneously moving a series of lifts from the stacks to said supports, and a conveyor having a lift moving member for successively moving the heel lifts one over another from the supports and progressively forming them into a heel pile. 90
4. In a heel building machine, the combination of means for holding a series of stacks of heel lifts, heel lift supports arranged in stepped relation with their supporting surfaces in different successively lower non-intersecting planes, means for simultaneously moving a series of heel lifts from the stacks to said lift supports, and means acting automatically to successively move the lifts from their supports and assemble them into a heel pile. 100
40. 5. In a heel building machine, the combination of means for holding a series of stacks of heel lifts, heel lift supports arranged in stepped relation with their lift supporting surfaces in different successively lower planes, means for simultaneously delivering a series of heel lifts from the stacks to the supports, an assembling pusher, and means for operating the pusher to cause it to successively advance the heel lifts and progressively assemble them into a heel pile. 110
45. 6. In a heel building machine, the combination of means for holding a series of stacks of heel lifts, heel lift supports arranged in a row adjacent the stacks and in stepped relation with their supporting surfaces in different successively lower planes, means for simultaneously removing a series of lifts from the stacks and delivering the lifts upon the respective stepped supports, an endless belt lift collector, and means for automatically moving it to successively engage the heel lifts and progressively form them into a heel pile. 120
7. In a heel building machine, the combination of heel lift supports arranged in stepped relation to support heel lifts in different planes, means for depositing heel lifts upon the stepped supports, a heel form, an assembling member, and means for actuating the assembling member in a single movement to assemble the lifts into a heel pile on the last lift support of the series and advance the pile to the heel form. 125
8. In a heel building machine, the combination of a series of heel lift magazines, a row of heel lift supports arranged in stepped relation to support heel lifts in alignment in different horizontal planes, means for depositing heel lifts from the magazines upon the stepped supports, a heel form adjacent the series of stepped supports, an assembling member, and means for actuating the assembling member to successively advance the heel lifts and form them into a heel pile and then transfer the pile to the heel form. 130
9. In a heel building machine, the combination of means for holding a series of stacks of heel lifts which have been previously supplied with an adhesive and dried, a support for heel lifts, means for simultaneously moving a series of lifts from the stacks and placing them on the support, means for moistening the adhesive surface of the lifts as they are moved towards the support, and assembling means for forming the lifts into a heel pile. 140
10. In a heel building machine, the combination of means for holding a series of stacks of heel lifts which have been previously supplied with an adhesive and dried, a support for heel lifts, means for simultaneously moving a series of lifts from the stacks and placing them on the support, a moistening pad past which the lifts are moved as they are fed towards the support for moistening the adhesive surfaces thereof, and means for assembling the lifts into a pile. 150
11. In a heel building machine, the combination of a series of magazines for holding heel lifts, a row of heel lift supports extending adjacent to the magazines and arranged in stepped relation from one end of the row to the other, a moistening pad arranged between the magazines and stepped supports for applying moisture to the upper surface of the lifts as they are fed to the supports, and assembling means for successively moving the lifts and forming them into a pile. 160
12. In a heel building machine, the combination of a series of magazines for holding heel lifts, a row of heel lift supports ex-

tending adjacent to the magazines and arranged in stepped relation from one end of the row to the other, a moistening pad arranged between the magazines and stepped supports and having moisture applying portions arranged in stepped relation for applying moisture to the upper surface of the lifts as they are fed to the supports, and assembling means for successively moving the lifts and forming them into a pile.

13. In a heel building machine, the combination of a series of magazines for holding heel lifts, a row of heel lift supports extending adjacent to the magazines and arranged in stepped relation from one end of the row to the other, a moistening pad arranged between the magazines and stepped supports and having moisture applying portions arranged in stepped relation for applying moisture to the upper surface of the lifts as they are fed to the supports, assembling means for successively moving the lifts and forming them into a pile, and means for applying water to the pad.

14. In a heel building machine, the combination of a series of heel lift magazines, a row of heel lift supports arranged in stepped relation and having a slot extending lengthwise of the row, means for depositing heel lifts from the magazines on the stepped supports, a pusher movable longitudinally of the row of supports in the said slot, and means for actuating the pusher to successively advance the heel lifts one over another longitudinally of the row of stepped supports and form them into a heel pile.

15. In a heel building machine, the combination of means for holding a series of stacks of heel lifts, heel lift supporting means adjacent to the series of magazines, means for simultaneously moving a plurality of heel lifts from the stack to the supporting means, a heel form having a movable side jaw, an assembling mechanism for forming the heel lifts into a pile and delivering the pile to the heel form, and means for opening the movable jaw to admit a pile of lifts and closing it after the pile has been delivered.

16. In a heel building machine, the combination of a heel form, an assembling mechanism for assembling heel lifts into a pile and delivering the pile to the heel form, a side jaw for the form movable to an open position to permit a pile of heel lifts to be moved into the form by the assembling mechanism, and means for opening and closing the side jaw.

17. In a heel building machine, the combination of heel lift assembling mechanism for advancing heel lifts in one direction and forming them into a pile, a heel form in alignment with the assembling mechanism and having a side jaw movable to an open position to permit a pile of assembled heel

lifts to be moved into the form, and means for opening the side jaw for the entrance of a pile of assembled heel lifts and for closing the side jaw after the pile has been placed in the form.

18. In a heel building machine, the combination of a heel form having side jaws one of which is movable to and from closed position, means for pressing a heel pile in the form, heel lift assembling mechanism for assembling lifts into a pile for delivery to the heel form, and means for opening the movable jaw when the assembling mechanism is operated that a heel pile may be passed into the form through the side thereof and closing the jaw when a heel pile has been delivered to the form.

19. In a heel building machine, the combination of a heel form, means for pressing a heel pile in the form, heel lift assembling means for assembling heel lifts into a pile outside of the form and delivering the pile to the form, separate means for operating the pressing means and assembling means, mechanism for alternately rendering one of said operating means operative and the other inoperative, and means for stopping the operation of the assembling means after each complete cycle of its movement.

20. In a heel building machine, the combination of a heel form, means for pressing a heel pile in the form, heel lift assembling mechanism for assembling heel lifts into a pile and then advancing the formed pile into the form, separate means for alternately operating the pressure means and assembling mechanism, means for opening the form to receive the pile of lifts from the assembling mechanism and for then closing the form, and means for stopping the operation of the assembling mechanism after each cycle of its movement.

21. In a heel building machine, the combination of a heel form, means for pressing a heel pile in the form, heel lift assembling means for assembling heel lifts into a pile for delivery to the form, separate means for operating the pressing means and assembling means, mechanism for alternately rendering one of said operating means operative and the other for inoperative, and means connected to the assembling mechanism for preventing operation of the pressing means during the operation of the assembling mechanism.

22. In a heel building machine, the combination of a heel form having a movable side member for opening and closing the form, means for pressing a pile of heel lifts in the form, lift assembling mechanism for collecting heel lifts into a pile and moving the formed pile of lifts into the form, and means connected to the assembling mechanism for preventing movement of the side member of the form to closing position until

after the delivery of a heel pile to the form.

23. In a heel building machine, the combination of a heel form having a fixed jaw and a movable jaw for opening and closing the form, means for pressing a pile of heel lifts in the form and movable to and from operative position, means for moving the movable jaw to open position when the presser means is moved to inoperative position, heel lift assembling mechanism for assembling heel lifts into a pile and advancing the formed pile to the form, and means connected to the assembling mechanism for preventing movement of the presser means to operative position until after the delivery of a pile of lifts to the form.

24. In a heel building machine, the combination of a heel form having a fixed jaw and movable jaw for opening and closing the form, means for pressing a pile of heel lifts in the form and movable to and from operative position, means for moving the movable jaw to open position when the presser means is moved to inoperative position, heel lift assembling mechanism for assembling heel lifts into a pile and advancing the formed pile to the form, means connected to the assembling mechanism for preventing movement of the pressure means to operative position until after the delivery of a pile of lifts to the form, and means for preventing operation of the assembling mechanism when the presser means is moved to operative position.

25. In a heel building machine, the combination of a series of magazines for holding stacks of heel lifts, a heel form, pressure means movable to and from operative position relative to the form, heel lift supporting means, and means actuated by movement of the pressure means to inoperative position to advance a series of heel lifts from the magazines to the lift supporting means.

26. In a heel building machine, the combination of a series of magazines for holding stacks of heel lifts, a heel form, pressure means movable to and from operative position relative to the form, heel lift supporting means, means actuated by movement of the pressure means to inoperative position to advance a series of heel lifts from the magazines to the lift supporting means, and lift assembling mechanism rendered operative by movement of the presser means to inoperative position to assemble the lifts on the supporting means into a pile for delivery to the form.

27. In a heel building machine, the combination of a heel form, a pressure head mounted for manual movement to and from operative relation to the form, means for holding a series of stacks of heel lifts, lift supporting means extending along the series of stacks, a series of pushers for simultaneously pushing a series of lifts from the

stacks and delivering them to the lift supporting means, and connections between the pushers and pressure head to effect operation of the pushers as the head is moved to inoperative position.

70

28. In a heel building machine, the combination of a heel form, a pressure head mounted for manual movement to and from operative relation to the form, means for holding a series of stacks of heel lifts, lift supporting means extending along the series of stacks, a series of pushers for simultaneously pushing a series of lifts from the stacks and delivering them to the lift supporting means, connections between the pushers and pressure head to effect operation of the pushers as the head is moved to inoperative position, and power actuated assembling mechanism for assembling the lifts into a pile for delivery to the form.

85

29. In a heel building machine, the combination of a heel form, a pressure head movable to and from operative position relative to the form to subject a pile of heel lifts to pressure, a heel ejector placed under spring tension by movement of the head to operative position over the form, and means for holding the ejector from its ejecting movement until pressure is applied to the heel pile in the form and then freeing it to eject the heel pile when the pressure is removed.

95

30. In a heel building machine, the combination of a heel form and pressure head, means for relatively moving them into a position to exert pressure on a heel pile in the form, an ejector placed under spring tension by relative movement of the head and form into a position to exert pressure, a catch for restraining movement of the ejector responsive to the spring tension, and means for tripping the catch when the heel pile is subjected to pressure.

100

31. In a heel building machine, the combination of a heel form having a jaw mounted to swing to and from closed position, means for assembling a pile of heel lifts and delivering the pile to the heel form, and means for swinging the jaw to open position and for starting the assembling mechanism into operation.

115

32. In a heel building machine, the combination of a series of lift supports arranged in stepped relation, a heel form having a fixed clamping portion and a movable clamping portion movable to and from closed or clamping position, an assembling mechanism, and means for automatically operating the assembling mechanism to successively advance the heel lifts from their supports and form them into a pile and then move the pile of lifts into the heel form and aline them against the fixed clamping portion.

120

In testimony whereof I have signed my name to this specification.

THOMAS LUND.
